Primary Examiner — Jennifer Rivard

Assistant Examiner — Alison M Ofstun

(57) CLAIM

The ornamental design for a lipstick box, as shown and described.

DESCRIPTION

FIG. 1 is a rear perspective view of a lipstick box showing my new design;

FIG. 2 is an exploded view thereof;

FIG. 3 is a front perspective view of the lipstick box cover thereof, shown separately to show aspects of the design not clearly visible when combined;

FIG. 4 is a front elevation view of FIG. 3;

FIG. 5 is a rear elevation view of FIG. 3;

FIG. 6 is a left side elevation view of FIG. 3;

FIG. 7 is a right side elevation view of FIG. 3;

FIG. 8 is a top plan view of FIG. 3;

FIG. 9 is a bottom plan view of FIG. 3;

FIG. 10 is a perspective view of the lipstick box base thereof, shown separately to show aspects of the design not clearly visible when combined;

FIG. 11 is a front elevation view of FIG. 10;

FIG. 12 is a rear elevation view of FIG. 10;

FIG. 13 is a left side elevation view of FIG. 10;

FIG. 14 is a right side elevation view of FIG. 10;

FIG. 15 is a top plan view of FIG. 10; and,

FIG. 16 is a bottom plan view of FIG. 10.

The broken lines depict portions of the lipstick box and form no part of the claimed design. The “KONDAL” is a registered trademark in China with a registered number 33733138, the applicant of the trademark is Shenzhen Shi Jin Zheng Jiang Da Metal & Plastic Ware Co. Ltd., the owner is also Shenzhen Shi Jin Zheng Jiang Da Metal & Plastic Ware Co. Ltd.
